Patents which have been issued in the name of and over which I have control and to reduce the risk of self destruction, the construction of which is a known to most men of skill, and will be described in the drawings and claims which follow. This invention relates to an improvement in the construction of an automobile door, and more particularly to a door which is capable of being automatically opened and closed, and also provides headroom for passengers entering and leaving the vehicle.

UNITED STATES PATENT OFFICE

2,647,790

AUTOMOBILE DOOR CONSTRUCTION

Edward L. Blackman, New York, N. Y.

Application April 9, 1952, Serial No. 281,384

3 Claims. (Cl. 296—44)

1

My invention relates to an improvement in automobile door construction and is an improvement on my Patent Number 2,535,347 issued December 26, 1950, and my application Serial Number 257,867, filed November 23, 1951.

One of the objects of my invention is to provide a simplified mechanism whereby a partial section of the roof of a vehicle may be carried by the door and is so arranged that this section is automatically swung out of the way when the door is opened and swung automatically back into position when the door is closed, thus providing additional headroom for passengers entering and leaving the vehicle.

Another object of my invention is to simplify the connections between the swingable top section and the operating mechanism so that positive opening and closure of the movable top section is effected with a minimum of parts.

Other objects and advantages will be apparent from the specification and drawings, in which—

Fig. 1 is a perspective of the door and swingable top piece showing the opening and closing mechanism with the door in open position;

Fig. 2 is a cutaway section of the top operating mechanism with the door in closed position;

Fig. 3 is an enlarged perspective of the top section operating mechanism with the door in closed position;

Fig. 4 is an enlarged perspective of the top section operating mechanism with the door in partially open position.

Referring to the drawings, 1 is the vehicle door supported on the frame 2 by means of the usual hinge 3. The door 1 has attached to it a cutaway portion 4 of the vehicle top 5 arranged as described in my aforementioned patent, and patent application so that the vehicle top 5 and cutaway portion 4 fit snugly together when the door 1 is closed.

The cutaway portion 4 is swingably supported on the door 1 by means of a hinge 6 of the type commonly referred to as a piano hinge wherein alternate strips of the door 1 and top section 4 are turned over and held in position by an axial rod 7 so that the hinged section 6 rotates freely on the rod 7 when the top section is raised or lowered.

Within a recess 8 in the door frame 2 a cable 9 is attached in any suitable manner such as by an eye bolt affixed to the door frame. The cable 9 is attached at the end away from the door frame to a sliding plate 10 by means of a holding bolt 11 which clamps the cable to projections 12 on the plate 10 as shown in Figs. 3 and 4. It will

50 and 55 indicate a pair of horizontal projections which extend at right angles to the longitudinal axis of the plate 10 and are positioned such that the cable 9 will be held in place when the plate 10 is moved laterally.

The plate 10 is so arranged that it may be moved laterally to position a slot 15 in the plate 10 such that the cable 9 will be held in place when the plate 10 is moved laterally.

FIG. 1 shows the door 1 in the closed position.

FIG. 2 shows the door 1 in the open position.

FIG. 3 shows the top section 4 in the closed position.

FIG. 4 shows the top section 4 in the open position.

FIG. 5 shows the top section 4 in the partially open position.

FIG. 6 shows the top section 4 in the fully open position.

FIG. 7 shows the top section 4 in the closed position.

FIG. 8 shows the top section 4 in the partially open position.

FIG. 9 shows the top section 4 in the fully open position.

FIG. 10 shows the top section 4 in the closed position.

FIG. 11 shows the top section 4 in the partially open position.

FIG. 12 shows the top section 4 in the fully open position.

FIG. 13 shows the top section 4 in the closed position.

FIG. 14 shows the top section 4 in the partially open position.

FIG. 15 shows the top section 4 in the fully open position.

FIG. 16 shows the top section 4 in the closed position.

FIG. 17 shows the top section 4 in the partially open position.

FIG. 18 shows the top section 4 in the fully open position.

FIG. 19 shows the top section 4 in the closed position.

FIG. 20 shows the top section 4 in the partially open position.

FIG. 21 shows the top section 4 in the fully open position.

FIG. 22 shows the top section 4 in the closed position.

FIG. 23 shows the top section 4 in the partially open position.

FIG. 24 shows the top section 4 in the fully open position.

FIG. 25 shows the top section 4 in the closed position.

FIG. 26 shows the top section 4 in the partially open position.

FIG. 27 shows the top section 4 in the fully open position.

FIG. 28 shows the top section 4 in the closed position.

FIG. 29 shows the top section 4 in the partially open position.

FIG. 30 shows the top section 4 in the fully open position.

FIG. 31 shows the top section 4 in the closed position.

FIG. 32 shows the top section 4 in the partially open position.

FIG. 33 shows the top section 4 in the fully open position.

FIG. 34 shows the top section 4 in the closed position.

FIG. 35 shows the top section 4 in the partially open position.

FIG. 36 shows the top section 4 in the fully open position.

FIG. 37 shows the top section 4 in the closed position.

FIG. 38 shows the top section 4 in the partially open position.

FIG. 39 shows the top section 4 in the fully open position.

FIG. 40 shows the top section 4 in the closed position.

FIG. 41 shows the top section 4 in the partially open position.

FIG. 42 shows the top section 4 in the fully open position.

FIG. 43 shows the top section 4 in the closed position.

FIG. 44 shows the top section 4 in the partially open position.

FIG. 45 shows the top section 4 in the fully open position.

FIG. 46 shows the top section 4 in the closed position.

FIG. 47 shows the top section 4 in the partially open position.

FIG. 48 shows the top section 4 in the fully open position.

FIG. 49 shows the top section 4 in the closed position.

FIG. 50 shows the top section 4 in the partially open position.

FIG. 51 shows the top section 4 in the fully open position.

FIG. 52 shows the top section 4 in the closed position.

FIG. 53 shows the top section 4 in the partially open position.

FIG. 54 shows the top section 4 in the fully open position.

FIG. 55 shows the top section 4 in the closed position.

FIG. 56 shows the top section 4 in the partially open position.

FIG. 57 shows the top section 4 in the fully open position.

FIG. 58 shows the top section 4 in the closed position.

FIG. 59 shows the top section 4 in the partially open position.

FIG. 60 shows the top section 4 in the fully open position.

FIG. 61 shows the top section 4 in the closed position.

FIG. 62 shows the top section 4 in the partially open position.

FIG. 63 shows the top section 4 in the fully open position.

FIG. 64 shows the top section 4 in the closed position.

FIG. 65 shows the top section 4 in the partially open position.

FIG. 66 shows the top section 4 in the fully open position.

FIG. 67 shows the top section 4 in the closed position.

FIG. 68 shows the top section 4 in the partially open position.

FIG. 69 shows the top section 4 in the fully open position.

FIG. 70 shows the top section 4 in the closed position.

FIG. 71 shows the top section 4 in the partially open position.

FIG. 72 shows the top section 4 in the fully open position.

FIG. 73 shows the top section 4 in the closed position.

FIG. 74 shows the top section 4 in the partially open position.

FIG. 75 shows the top section 4 in the fully open position.

FIG. 76 shows the top section 4 in the closed position.

FIG. 77 shows the top section 4 in the partially open position.

FIG. 78 shows the top section 4 in the fully open position.

FIG. 79 shows the top section 4 in the closed position.

FIG. 80 shows the top section 4 in the partially open position.

FIG. 81 shows the top section 4 in the fully open position.

FIG. 82 shows the top section 4 in the closed position.

FIG. 83 shows the top section 4 in the partially open position.

FIG. 84 shows the top section 4 in the fully open position.

FIG. 85 shows the top section 4 in the closed position.

FIG. 86 shows the top section 4 in the partially open position.

FIG. 87 shows the top section 4 in the fully open position.

FIG. 88 shows the top section 4 in the closed position.

FIG. 89 shows the top section 4 in the partially open position.

FIG. 90 shows the top section 4 in the fully open position.

FIG. 91 shows the top section 4 in the closed position.

FIG. 92 shows the top section 4 in the partially open position.

FIG. 93 shows the top section 4 in the fully open position.

FIG. 94 shows the top section 4 in the closed position.

FIG. 95 shows the top section 4 in the partially open position.

FIG. 96 shows the top section 4 in the fully open position.

FIG. 97 shows the top section 4 in the closed position.

FIG. 98 shows the top section 4 in the partially open position.

FIG. 99 shows the top section 4 in the fully open position.

FIG. 100 shows the top section 4 in the closed position.

FIG. 101 shows the top section 4 in the partially open position.

FIG. 102 shows the top section 4 in the fully open position.

FIG. 103 shows the top section 4 in the closed position.

FIG. 104 shows the top section 4 in the partially open position.

FIG. 105 shows the top section 4 in the fully open position.

FIG. 106 shows the top section 4 in the closed position.

FIG. 107 shows the top section 4 in the partially open position.

FIG. 108 shows the top section 4 in the fully open position.

FIG. 109 shows the top section 4 in the closed position.

FIG. 110 shows the top section 4 in the partially open position.

FIG. 111 shows the top section 4 in the fully open position.

FIG. 112 shows the top section 4 in the closed position.

FIG. 113 shows the top section 4 in the partially open position.

FIG. 114 shows the top section 4 in the fully open position.

FIG. 115 shows the top section 4 in the closed position.

FIG. 116 shows the top section 4 in the partially open position.

FIG. 117 shows the top section 4 in the fully open position.

FIG. 118 shows the top section 4 in the closed position.

FIG. 119 shows the top section 4 in the partially open position.

FIG. 120 shows the top section 4 in the fully open position.

FIG. 121 shows the top section 4 in the closed position.

FIG. 122 shows the top section 4 in the partially open position.

FIG. 123 shows the top section 4 in the fully open position.

FIG. 124 shows the top section 4 in the closed position.

FIG. 125 shows the top section 4 in the partially open position.

FIG. 126 shows the top section 4 in the fully open position.

FIG. 127 shows the top section 4 in the closed position.

FIG. 128 shows the top section 4 in the partially open position.

FIG. 129 shows the top section 4 in the fully open position.

FIG. 130 shows the top section 4 in the closed position.

FIG. 131 shows the top section 4 in the partially open position.

FIG. 132 shows the top section 4 in the fully open position.

FIG. 133 shows the top section 4 in the closed position.

FIG. 134 shows the top section 4 in the partially open position.

FIG. 135 shows the top section 4 in the fully open position.

FIG. 136 shows the top section 4 in the closed position.

FIG. 137 shows the top section 4 in the partially open position.

FIG. 138 shows the top section 4 in the fully open position.

FIG. 139 shows the top section 4 in the closed position.

FIG. 140 shows the top section 4 in the partially open position.

FIG. 141 shows the top section 4 in the fully open position.

FIG. 142 shows the top section 4 in the closed position.

FIG. 143 shows the top section 4 in the partially open position.

FIG. 144 shows the top section 4 in the fully open position.

FIG. 145 shows the top section 4 in the closed position.

FIG. 146 shows the top section 4 in the partially open position.

FIG. 147 shows the top section 4 in the fully open position.

FIG. 148 shows the top section 4 in the closed position.

FIG. 149 shows the top section 4 in the partially open position.

FIG. 150 shows the top section 4 in the fully open position.

FIG. 151 shows the top section 4 in the closed position.

FIG. 152 shows the top section 4 in the partially open position.

FIG. 153 shows the top section 4 in the fully open position.

FIG. 154 shows the top section 4 in the closed position.

FIG. 155 shows the top section 4 in the partially open position.

FIG. 156 shows the top section 4 in the fully open position.

FIG. 157 shows the top section 4 in the closed position.

FIG. 158 shows the top section 4 in the partially open position.

FIG. 159 shows the top section 4 in the fully open position.

FIG. 160 shows the top section 4 in the closed position.

FIG. 161 shows the top section 4 in the partially open position.

FIG. 162 shows the top section 4 in the fully open position.

FIG. 163 shows the top section 4 in the closed position.

FIG. 164 shows the top section 4 in the partially open position.

FIG. 165 shows the top section 4 in the fully open position.

FIG. 166 shows the top section 4 in the closed position.

FIG. 167 shows the top section 4 in the partially open position.

FIG. 168 shows the top section 4 in the fully open position.

FIG. 169 shows the top section 4 in the closed position.

FIG. 170 shows the top section 4 in the partially open position.

FIG. 171 shows the top section 4 in the fully open position.

FIG. 172 shows the top section 4 in the closed position.

FIG. 173 shows the top section 4 in the partially open position.

FIG. 174 shows the top section 4 in the fully open position.

FIG. 175 shows the top section 4 in the closed position.

FIG. 176 shows the top section 4 in the partially open position.

FIG. 177 shows the top section 4 in the fully open position.

FIG. 178 shows the top section 4 in the closed position.

FIG. 179 shows the top section 4 in the partially open position.

FIG. 180 shows the top section 4 in the fully open position.

FIG. 181 shows the top section 4 in the closed position.

FIG. 182 shows the top section 4 in the partially open position.

FIG. 183 shows the top section 4 in the fully open position.

FIG. 184 shows the top section 4 in the closed position.

FIG. 185 shows the top section 4 in the partially open position.

FIG. 186 shows the top section 4 in the fully open position.

FIG. 187 shows the top section 4 in the closed position.

FIG. 188 shows the top section 4 in the partially open position.

FIG. 189 shows the top section 4 in the fully open position.

FIG. 190 shows the top section 4 in the closed position.

position, all rattle or play is prevented due to the enlargements 18 and 19 being in close tolerance with the cross section of the "lazy S" cam surfaces at each end.

On closure of the door, the ring bolt 28 is forced down the slope of the surface of the "lazy S" cam 16 by the action of the spring 23 forcing the plate along the slot 15 so that a positive closure of the top section 4 is effected.

I claim:

1. In a device of the character described, in combination with a door, a frame for said door, a hinge on which said door is mounted in said frame, a fixed top having a recess above the door, a top section of the door corresponding to said recess and hingedly mounted on the top of the door near one edge thereof and constructed and arranged to open and close said recess and to swing up and down when the door is opened and closed respectively, a slidable plate mounted on said door carrying a pivotally mounted cam, a contact arm operatively connected with the surface of said cam at one end and rigidly attached to said top section of the door at its other end, means attached to said frame for preventing displacement of said slidable plate when said door is opened whereby said contact arm raises said top section when the door is opened and lowers said top section when the door is closed.

2. In a device of the character described, in combination with a door, a frame for said door, a hinge on which said door is mounted in said frame, a fixed top having a recess above the door, a top section of the door corresponding to said recess and hingedly mounted on the top of the door near one edge thereof and constructed and arranged to open and close said recess and to swing up and down when the door is opened and closed respectively, a slidable plate mounted on said door carrying a pivotally mounted cam, a contact arm operatively connected with the sur-

face of said cam at one end and rigidly attached to said top section of the door at its other end, means attached to said frame for preventing displacement of said slidable plate when said door is opened whereby said contact arm is forced to ride up, the surface of said cam when the door is opened causing said top section to raise, and a spring member which forces said contact arm to ride down said cam when said door is opened causing a lowering of said section.

3. In a device of the character described, in combination with a door, a frame for said door, a hinge on which said door is mounted in said frame, a fixed top having a recess above the door, a top section of the door corresponding to said recess and hingedly mounted on the top of the door near one edge thereof and constructed and arranged to open and close said recess and to swing up and down when the door is opened and closed respectively, a slidable plate mounted on said door carrying a pivotally mounted cam, a contact arm operatively connected with the surface of said cam at one end and rigidly attached to said top section of the door at its other end, a cable attached at one end of said slidable plate and at the other end of said door frame for preventing displacement of said slidable plate when said door is opened whereby said contact arm is forced to ride the surface of said cam when the door is opened causing said top to raise, and a spring member which forces said contact arm to ride down said cam when said door is closed causing the lowering of said top section.

EDWARD L. BLACKMAN.
